US00D923129S

(12) **United States Design Patent** (10) Patent No.: **US D923,129 S**
(45) Date of Patent: **** Jun. 22, 2021**

(54) **FREE FLOATING HANDGUARD
ANCHORING SYSTEM**

(71) Applicant: **Springfield, Inc.**, Geneseo, IL (US)
(72) Inventor: **Charles David Williams**, Geneseo, IL (US)

(73) Assignee: **Springfield, Inc.**

(**) Term: **15 Years**

(21) Appl. No.: **29/606,940**

(22) Filed: **Jun. 8, 2017**

(51) LOC (13) Cl. **22-01**

(52) U.S. Cl.

USPC **D22/108**

(58) **Field of Classification Search**

USPC **D22/108; D21/572-576**

CPC **F41C 23/16; F41C 27/00**

See application file for complete search history.

(57) **CLAIM**

The ornamental design for a free floating handguard anchoring system, as shown and described.

DESCRIPTION

FIG. 1 is a rear perspective view of a first embodiment of a free floating handguard anchoring system;
FIG. 2 is a front perspective view thereof;
FIG. 3 is a top view thereof;
FIG. 4 is a bottom view thereof;
FIG. 5 is a left side view thereof;
FIG. 6 is a right side view thereof;
FIG. 7 is a rear end view thereof;
FIG. 8 is a front end view thereof;
FIG. 9 is a rear perspective of a second embodiment of a free floating handguard anchoring system;
FIG. 10 is a front perspective view thereof;
FIG. 11 is a top view thereof;
FIG. 12 is a bottom view thereof;
FIG. 13 is a left side view thereof;
FIG. 14 is a right side view thereof;
FIG. 15 is a rear end view thereof; and,
FIG. 16 is a front end view thereof.

1 Claim, 6 Drawing Sheets
